ATTORNEY

UNITED STATES PATENT OFFICE

GEORGE W. BINNS, OF CINCINNATI, OHIO, ASSIGNOR TO CINCINNATI GRINDERS INCORPORATED, OF CINCINNATI, OHIO, A CORPORATION OF OHIO

GRINDING MACHINE

Application filed September 2, 1930. Serial No. 479,237.

This invention relates to improvements in machine tools and especially to improvements in centerless grinding machines.

An object of the invention is the provision of improved means for positioning a work piece relative to the throat of a centerless grinder.

Another object of the invention is the provision of an improved hydraulic or pneumatic work ejecting mechanism utilizable with a fixed or immovable stop mechanism thereby insuring proper positioning of work relative to the grinding wheels of a centerless grinder and this mechanism is especially advantageous for the tooling of formed or tapered work pieces, such as the valve seats of mushroom type valves, taper bearing rolls, and such like articles.

An additional object of the invention is the provision of such a positioning and ejecting mechanism which, when utilized while machining or finishing as above noted formed or tapered work, will bear against the work at a point as closely as possible coincident with the axis of rotation thereof so that no interference to the rotation of the work is offered by the said positioning or stop member.

Other objects and advantages of the present invention should be readily understood by reference to the following specification considered in conjunction with the accompanying drawings and it is to be understood that any modifications may be made within the exact structural details there shown and described within the scope of the appended claims without departing from or exceeding the spirit of the invention.

In the drawings:

Figure 1 is a front elevational view of a grinding machine embodying the improvements of this invention.

Figure 2 is a top plan view of the machine shown in Figure 1.

Figure 3 is a sectional view taken on line 3-3 of Figure 1.

Figure 4 is a sectional view taken substantially on line 4-4 of Figure 2.

Figure 5 is a sectional view taken substantially on line 5-5 of Figure 2.

Figure 6 is a fragmentary sectional view taken on line 6-6 of Figure 4.

Figure 7 is an end view partly in section of the machine shown in Figure 1 illustrating a modification of the invention.

Figure 8 is a modified form of the invention.

Throughout the several views of the drawings similar reference characters are employed to denote the same or similar parts.

In the use of centerless grinders there are two methods generally employed known as the through-feed and in-feed methods. In the former method the work is introduced into the grinding throat of a centerless grinder at one side thereof and fed axially through the said throat to be discharged on the other side thereof while in the in-feed method the grinding throat is enlarged to permit the insertion of work therein, the throat is then contracted to reduce the work to the desired size and form and subsequently enlarged permitting removal of the work from the same side of the throat as it was introduced. This invention pertains primarily to the in-feed method of grinding although it may be used with the through-feed method. In the past, the normal stop means for positioning the work in the grinding throat relative to the grinding wheel was made movable and served the double function of positioning and ejecting member. It has been found that for certain types of work an absolutely rigid end stop is desirable which should bear against the work very close to its center of rotation.

These advantages are realized by the use of the device of this invention illustrated in the drawings and such a device may comprise a bed 10 having rotatably mounted at one end thereof a grinding wheel 11 rotatable at a high or grinding rate of speed in a clockwise direction as indicated by the arrow on its housing. Opposed to the grinding wheel 11 and movably supported by the bed 10 is a regulating wheel 12 likewise rotatable in a clockwise direction but at a relatively slow, work controlling rate of speed. The regulating wheel 12 is supported for rotation by a slide or housing 13 forming a part of the regulating wheel unit and supported on suit-

able ways for movement therealong by the lower slide 14. This slide is in turn guided on ways 15 formed on the upper surface of the bed 10. The opposed active faces of the 5 grinding and regulating wheels are adapted to be spaced from one another to form a grinding throat in which the work 16 is mounted for operation thereon. The said work 16 is supported by a work rest blade 17 having 10 active angled top 18 inclining toward the face of the regulating wheel 12 and forming a work receivinig trough therewith. The blade 17 is supported by a work rest block 19 carried by the inner end of the lower 15 slide 14.

The lower slide 14 is adapted to be translated along the bed 10 for adjusting the work rest block 19 relative to the grinding throat for initially setting-up the machine while the 20 regulating wheel unit 13 is movable longitudinally of the said lower slide for feeding the work carried by the blade 17 into the grinding wheel to effect a stock removal therefrom. The said slides are further adapted to 25 be moved as a unit relative to the bed 10 especially when setting-up the grinding throat for which purpose clamp 20 is provided for securing the said slides to one another while to permit independent movement of the regulating wheel unit clamps 21 are employed 30 for locking the lower slide to the bed 10. An adjusting screw 22 is employed for actuating the slides and has its threaded end received in a nut 23, see Figure 5, carried by the regulating wheel unit 13 and held against translating movement relative thereto by collars or the like 24. A pilot or hand wheel 25 is mounted on the outer end of the adjusting screw 22 for actuating same.

40 As shown in Figures 1, 2, 4 and 5, the upper slide 13, in actual operation, is automatically moved through a definite zone by the in-feed mechanism enclosed within housing 26 secured to the bed 10. A worm shaft 27 is 45 rotatably journaled in the housing 26 and has keyed to its one end a worm wheel 28 operatively coupled with worm 29. Secured to the worm shaft at its outer end thereof is a gear 30 connected to change gears 31 with a motor 32 carried by the housing 26. The motor 32 imparts rotation to the shaft 27 for driving a cam 33 mounted on the opposite end thereof. As shown in Figure 5, the cam 33 is provided with a groove 34 receiving there- 50 in a roller 35 carried by adjustable block 36 on the lower end of arm 37. The arm 37 is pivoted at 38 to the walls of the housing 26 and has extending therefrom lugs 39. Links 40 have one of their ends pivoted to the lugs 39 and their other end to a slide block 41 slidable in a bearing 42 of the housing 26. The slide block 41 surrounds the adjusting screw 22 and is secured in position thereon by collars 43 and 44.

60 From the foregoing it will be noted that

the cam groove 34 oscillates the arm 37 about its pivot for axially shifting the screw 22 thereby feeding the regulating wheel 12 toward the grinding wheel 11 and retracting same therefrom. This cam groove is so arranged that a rapid movement is first imparted to the regulating wheel unit toward the grinding wheel followed by a slow work feeding movement and then a rapid retraction thereof, for which purpose the portion 75 34a of the groove is employed.

Supported by the work rest block 19 at the rear end of the grinding throat is a bracket 45 having a threaded bore 46 therein aligning with the grinding throat and receiving a 80 positioning member 47. The said positioning member is provided with a central bore 48 and a threaded shank 49 for lock nut 50 for positively locking the positioning member 47 relative to the bracket 45. The lower end of the bracket 45 is provided with an elongated opening 51 for bolt 52 which extends therethrough into the work rest block 19. The elongated opening 51 permits a vertical adjustment of the bracket 45 relative 85 to the block 19 whereby the threaded bore 46 therein may be properly aligned with the grinding throat. The bracket 45 is further provided with a reduced threaded bore 53 co-axial with bore 46 and receiving pipe or 90 hose coupling 54 from which air pipe or conduit 55 extends.

The said conduit 55 extends to one end of the machine where it is coupled with valve block 56 secured to the housing 26. The said valve block 56 encloses a conical valve 57 having a spring 58 engaging its one end and normally holding it against its seat 59. A rod 60 abuts on one end with the other side of the valve being guided through gland 61. The other end of the rod 60 abuts an arm 62 fast on the end of rock shaft 63. As shown in Figure 4, the rock shaft 63 is oscillatably journaled in the walls of the housing 26 and has secured to it intermediate its ends an arm 64 carrying roller 65 which rides on the periphery 66 of the cam 33 for engagement with cam lug 67 formed on the said periphery 66. A pressure conduit or line 68 is also connected with the valve block 56 being closed off by the 105 valve 57.

The relation of cam lug 67 and portion 34a of the cam groove 34 is such that the regulating wheel is first retracted from the grinding wheel for opening the throat thereof whereupon the cam lug 67 engages roller 65 for oscillating the arm 63 and opening the valve 57 to connect pressure conduit 68 with the conduit 55 causing a blast of air to flow through the bore 48 of the positioning member 47 for ejecting a piece of work from the grinding throat. As soon as the cam lug 67 passes from under the roller 65 the spring 58 expands and returns the valve 57 to its seat cutting off further flow of the compressed air 110 120 125 130

through the conduit 55 so that an additional work piece may be positioned within the grinding throat.

The modified work positioning and ejecting structure shown in Figure 8 is particularly useful in the grinding of formed work pieces, and as shown is utilized for positioning a tapered bearing roll. The said mechanism comprises an adjustable bracket 5 or supporting member 45a having a threaded bore 80 receiving the threaded shank of end stop or positioning member 81. The bracket 45a is further provided with an enlarged aperture 82 through which the reduced abutting portion 83 of the stop member 81 extends. This reduced portion 83 terminates in a nose 84 abutting the rear end of the work or tapered bearing roll 85. The walls of the bracket member 45a are spaced from the surface of the abutting portion 83—84 to provide a passage and form a nozzle for the hydraulic medium, such as compressed air, for directing same against the end of the work. The hydraulic pressure medium 20 or air is introduced into the chamber 82 through a suitable conduit or hose 55a.

From the foregoing it will be noted that a positive immovable end stop has been provided for engaging the work at a point substantially co-axial with the center of rotation. By this construction interference to the rotation of the work is reduced to an absolute minimum even though the portion or end of the work contacting with the stop 30 or positioning member is not absolutely normal to the axis of rotation and it will be noted that sufficient surface of the work is exposed to the action of the hydraulic medium or air blast.

40 The modification, shown in Figure 7, is of a semi-automatic nature in that the regulating wheel is actuated toward and from the grinding wheel manually while the valve for operating the compressed air ejector is opened automatically at the end of the retracting movement of the regulating wheel by the said lever. This mechanism includes the manually shiftable lever 70 secured through split clamp 71, at the lower end 45 thereof, to the nut 23 which is oscillatably mounted in the regulating wheel unit or slide 13. The said lever 70 is normally in the position shown in dotted lines at 72 at which time the grinding throat is enlarged for the reception of an unfinished work piece. A valve housing 73 is secured to the rear wall of the regulating wheel unit 13 and has extending therefrom a valve plunger 74 for valve 75 held against its seat by a spring 76. An additional spring 77 surrounds the plunger 74 for normally holding the valve 75 closed and preventing flow of the compressed air from conduit 68 to conduit 55. For actuating the valve plunger 74 there is provided 50 for movement with the lever 70 a trigger

member 78 adapted to engage the head of the plunger 74.

The operation of the device disclosed in Figure 7 is as follows: With the hand lever in the position shown by the dotted lines 72 70 a work piece is placed upon the work rest blade 17 whereupon the lever 70 is actuated in a counter clockwise direction feeding the regulating wheel unit 13 and regulating wheel 12 toward the grinding wheel. The movement of the lever 70 is substantially through an arc of 90° at which time a slight pause is effected for permitting the sparking out of the grinding wheel whereupon the lever is reversely actuated or moved in a 75 clockwise direction. This movement continues to and beyond the dotted line position for causing the trigger member 78 to engage and depress the plunger 74 opening the valve and connecting the conduits 68 and 55. At this time the grinding throat is completely expanded and the sudden blast of compressed air ejects the work from the grinding throat. The lever may then be returned to its normal dotted line position permitting springs 77 and 76 to expand and close the valve or the manual force against the lever may be removed after opening the valve and permit the lever to be returned to its normal position by the said springs. 80 90 95

What is claimed is:

1. In a device of the class described the combination with a bed, of a pair of opposed grinding and regulating wheels carried thereby and forming a grinding throat therebetween, a work rest blade within the throat for supporting work in engagement with the wheels, a fixed stop member adjacent the work rest for positioning a work piece on the work rest relative to the wheels, the said fixed stop member having an axial opening therethrough, a pneumatic pressure source, and means connecting the pneumatic pressure source with the stop member whereby the said pneumatic pressure source is directed 100 against the end of the work contacting the fixed stop for ejecting same from the work rest blade. 105 110
2. In a device of the class described the combination with a pair of opposed grinding and regulating wheels forming a grinding throat therebetween, of a work support within the throat for supporting a work piece, a source of hydraulic pressure, a hollow fixed stop member for abutment with the work on 115 the work rest blade to position said work relative to the blade and connected with the pressure source for directing same against the work to eject the work from the grinding throat, and means intermittently actuatable 120 for controlling the flow from the pressure source to eject the work from its support after the grinding operation. 125
3. In a device of the class described the combination with a pair of opposed grinding 130

and regulating wheels forming a grinding throat therebetween, of a work support within the throat for supporting a work piece, a source of hydraulic pressure, a hollow fixed stop member for abutment with the work on the work rest blade to position said work relative to the blade and connected with the pressure source for directing same against the work to eject the work from the grinding throat, means controlling the flow of the pressure source, means for actuating one of the wheels toward the other to feed the work into the grinding wheel, and means operable with the work feeding means for actuating the pressure flow control means.

4. In a device of the class described the combination of a work support for peripherally supporting a work piece, a bracket adjacent said support, a hollow positioning member carried by the bracket for abutment with the work to position the work relative to the work support, and an hydraulic pressure source, in the nature of a gas, coupled with the hollow work positioning member and directed thereby against the work for axially ejecting the work from the support.

5. In a device of the class described the combination of a work support for peripherally supporting a work piece, a bracket adjacent said support, a hollow positioning member carried by the bracket for abutment with the work to position the work relative to the work support, an hydraulic pressure source coupled with the hollow work positioning member and directed thereby against the work for ejecting the work from the support, a grinding wheel for operation on the work to effect a stock removal therefrom, means for feeding the work into the grinding wheel, and means operable by said work feeding means for controlling the flow of the pressure source.

6. In a device of the class described the combination of a bed, a grinding wheel rotatably carried thereby, a slide translatable carried by the bed for movement toward and from the grinding wheel, a work rotation controlling member carried by the slide for movement therewith, means between the active faces of the wheels for supporting a work piece during the grinding operation, means for abutting the work to restrain the work against axial movement during the grinding operation, means for translating the slide and regulating wheel toward the grinding wheel including a cam, means for directing a blast of compressed air against the work for actuating said work relative to the support to eject same from the grinding throat, and means controlling the flow of said compressed air operable by the cam.

7. In a device of the class described the combination of a pair of opposed grinding and regulating wheels forming a grinding throat therebetween, a work support within

the grinding throat, means for actuating one of the wheels toward the other to feed the work into the grinding wheel to effect a stock removal therefrom including a manually actuatable lever, means for directing a blast of compressed air against the work for ejecting same from the blade, and means operable by the lever for controlling the flow of the said compressed air.

8. In a device of the class described the combination with a work support for peripheral engagement with the work, a bracket adjacent the support having a threaded bore aligned with the work, a positioning nozzle having a threaded shank received in the threaded bore of the bracket and abutting the work to position same relative to the support, means for locking the positioning nozzle in its adjusted position, and an hydraulic pressure source terminating at the bracket and directed by the positioning nozzle against the work to eject said work from its support.

9. In a device of the class described the combination of a pair of opposed grinding and regulating wheels forming a grinding throat therebetween, means within the throat for peripherally supporting a work piece while in engagement with the said wheels, an immovable positive stop member for abutting the work to position same relative to the support means and grinding throat, and means for directing a blast of air against the work to eject same from the grinding throat.

10. In a device of the class described the combination with the throat of a centerless grinder including means therein for peripherally supporting a work piece, of means for positioning the work relative to the supporting means and grinding throat and for ejecting same therefrom comprising a supporting bracket, an immovable abutment member carried by said bracket contacting with the work at a point substantially coincident with the axis of rotation thereof, and means for directing a blast of air against the work to eject same from the grinding throat.

11. In a device of the class described the combination with the throat of a centerless grinder including means therein for peripherally supporting a work piece, of means for positioning the work relative to the supporting means and grinding throat and for ejecting same therefrom comprising a supporting bracket, an immovable abutment member carried by said bracket contacting with the work at a point substantially coincident with the axis of rotation thereof, means for directing a blast of air against the work to eject same from the grinding throat, said means comprising a chamber formed in the bracket surrounding the positioning member, and means for supplying the compressed air to the chamber.

12. In a device of the class described the

combination with the throat of a centerless grinder including means therein for peripherally supporting a work piece, of means for positioning the work relative to the supporting means and grinding throat, and for ejecting same therefrom comprising a supporting bracket, an immovable abutment member carried by said bracket contacting with the work at a point substantially coincident with the axis of rotation thereof, means for directing a blast of air against the work to eject same from the grinding throat, said means comprising a chamber formed in the bracket surrounding the positioning member, means for supplying the compressed air to the chamber, and means for adjustably locking the abutment member in adjusted position relative to the bracket.

13. In a device of the class described the
20 combination with the throat of a centerless

grinder including means therein for peripherally supporting a work piece, of means for positioning the work relative to the supporting means and grinding throat and for ejecting same therefrom comprising a supporting bracket, an immovable abutment member carried by said bracket contacting with the work at a point substantially coincident with the axis of rotation thereof, means for directing a blast of air against the work to 70 eject same from the grinding throat, said means comprising a chamber formed in the bracket surrounding the positioning member, means for supplying the compressed air to the chamber, and means controlling the flow 75 of the compressed air to the chamber whereby a blast thereof is directed against the work 80 only at the completion of the grinding operation.
